CLAIM

The ornamental design for the water treatment vessel emptying device, as shown and described.

DESCRIPTION

FIG. 1 is a perspective angled front view of the water treatment vessel emptying device, which embodies my design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective angled front view thereof in use; and, FIG. 9 is another perspective angled front view thereof in use.

Portions of the drawings shown in broken lines form no part of the claimed design.

1 Claim, 7 Drawing Sheets
